CARL GUSTAF SWEBILIUS, OF NEW HAVEN, CONNECTICUT, ASSIGNOR TO THE MARLIN FIREARMS CORPORATION, OF NEW HAVEN, CONNECTICUT, A CORPORATION OF DELAWARE.

AUTOMATIC FIREARM.

Application filed January 17, 1922. Serial No. 529,958.

To all whom it may concern:

Be it known that I, CARL GUSTAF SWEBILIUS, a citizen of the United States, residing at New Haven, in the county of New Haven 5 and State of Connecticut, have invented a new and useful Improvement in Automatic Firearms, of which the following is a specification.

This invention relates to firearms and 10 pertains more especially to automatic rifles, shotguns and pistols.

The gas pressure within the barrel of a gun immediately after the explosion is of the order of several thousand pounds to the 15 square inch but decreases to a much lower pressure to the square inch as the projectile nears the muzzle of the barrel. The pressure of the gas immediately after the explosion is too great to be safely utilized to operate 20 the mechanism of a gun, yet the subsequent decreased pressure is low enough to be safely used. In the operation of automatic guns, the breech mechanism is locked in its closed position during the period that the gas pressure 25 is at its maximum power. After the gas pressure has decreased to a safe power, the gas pressure, exerted through suitable mechanism, is then utilized to release the breech lock and reloading mechanism of the 30 gun.

A previous method of locking the breech mechanism has been to provide an abutment slideway inclined to the axis of the barrel and a locking member adapted to be 35 movably clamped against said abutment by the high discharge gas pressure within the barrel transmitted to said locking member through the medium of the cartridge shell. The locking member is relieved from said 40 clamping condition upon the decrease of gas pressure within the barrel to allow the locking member to move out of locking position under the influence of the lower gas pressure.

An object of my invention is the direct 45 positive application of the high pressure of the gas within the barrel immediately after the explosion of a cartridge to means for locking the breech mechanism in its 50 closed position, and the subsequent release of said locking means, upon the decrease of the gas pressure, to allow the decreased gas pressure to operate the breech mechanism.

An additional object of the invention is

to improve generally upon automatic guns 55 by simplifying the structure and materially reducing the number of elements composing the guns.

These and other objects of the invention, which objects will be apparent from the following specification and accompanying drawings, are accomplished generally by providing ports in the barrel, forward of the chamber, which direct the gas against movable locking members arranged to bear 65 against a portion of the breech mechanism. The clamping effect of these members when pressed against the portion of the breech mechanism by the high pressure of the gas in the barrel immediately after the explosion 70 is sufficient to lock the breech mechanism in its closed position. The reduction of the gas pressure as the projectile passes along the barrel releases the lock effect, and the breech mechanism is then operated by the 75 pressure of the gas bearing against it through the medium of the cartridge shell.

This invention will be better understood by having reference to the following specification and accompanying drawing wherein Fig. 1 is a longitudinal section of a gun disclosing an embodiment of the invention, the rear end of the receiver and the front end of the barrel being broken off; Fig. 2 is a section on the line 2—2 of Fig. 1 80 and Fig. 3 is a section on the line 3—3 of Fig. 1.

Into the front wall of the receiver 10 is screwed the barrel 11. Extending longitudinally of the barrel along its lower portion are the ribs 12. The breech bolt 13 is reciprocatively mounted in the receiver and has projecting forwardly therefrom the arms 14 which pass through the front wall of the receiver and are joined together at 95 their forward ends by the cross member 15. Each of these arms 14 is provided with a groove 16 receiving one of the ribs 12. A rod 17 extends from the abutment 27 on the bottom plate 25, the abutment forming 100 a part of the front wall of the receiver, and said rod is arranged between the arms 14. The forward end of the rod 17 extends through an aperture in the member 15. A helical spring 18 surrounds the rod 17 and 105 its forward end fits in and abuts against the bottom of a socket in the member 15.

In the barrel, beginning just slightly in

advance of the cartridge chamber, is a series of ports 19 which communicate with the sockets 20. These sockets are preferably symmetrically arranged with respect to and 5 at an angle to the vertical plane passing through the axis of the barrel, although they may be arranged in any other desired manner. In each socket is provided a plunger 21 which, when in one position, projects beyond the surface of the barrel and 10 its end engages a socket in one of the arms 14. The design of the ends of the plungers and of the sockets is such that when the plungers are forced into the sockets by the 15 high gas pressure present in the barrel immediately after the explosion of the cartridge, the faces of the plungers and of the sockets will stick or lock to each other so tightly as to prevent relative movement of 20 said faces under the influence of the pressure exerted rearwardly against the breech bolt through the medium of the cartridge shell. 25 A firing pin 22 is reciprocatively mounted in the breech bolt 10 and a hammer 23 is pivotally supported in the receiver to cooperate therewith. A trigger 24 in the bottom plate 25 serves to hold the hammer in cocked position. Extending through a slot in the bottom plate is a magazine 26. 30 The operation of this gun is as follows: When the breech bolt is in its closed position as shown in Fig. 1, the plungers move, preferably by gravity, into the sockets in the arms 14. Immediately after the explosion 35 of the cartridge, the gas pressure in the barrel rises to an extremely high power. The plungers 21 are forced into the sockets so strongly by reason of this pressure that the faces of the plungers and the sockets stick or lock to each other sufficiently to prevent the 40 sliding of one on the other and this prevents rearward movement of the breech bolt notwithstanding the pressure exerted against it through the head of the cartridge case following the explosion. As the bullet approaches the front end of the barrel, the gas pressure diminishes to a condition where the sticking or locking of the faces of the 45 plungers and sockets ceases. The pressure exerted on the breech bolt through the head of the cartridge then causes the breech bolt to move rearwardly, the plungers being raised up out of the sockets by the sliding of their faces over the faces of the sockets. The 50 design of the faces of the plungers and sockets may be varied to meet different conditions and it is within the contemplation of this invention that the faces of the plungers may be smooth and contact with the surface of 55 the arms, the sockets being dispensed with. The number of plungers may also be varied as desired to obtain the effect described. 60 It is, of course, obvious that various other modifications may be made in the structure and design of this type of gun without in 65

any way departing from the spirit of the invention as set forth in the appended claims.

What I claim is:

1. In an automatic firearm, a receiver, a barrel carried thereby, a breech mechanism having a portion mounted in said receiver, and means for locking said breech mechanism in closed position, said means comprising a movable member forward of said receiver and bearing against a portion of said breech mechanism, said member being subject directly to the gas pressure within the barrel, the locking action of said means being due solely to the gas pressure. 75
2. In an automatic firearm, a receiver, a barrel carried thereby, a breech mechanism having a portion movably mounted in said receiver, a movable member forward of said receiver and adapted to bear against a portion of said breech mechanism to lock said breech mechanism in closed position and means to subject said member directly to the gas pressure within the barrel, the locking action of said means being due solely to the gas pressure. 85
3. In an automatic firearm, a receiver, a barrel carried thereby, a breech mechanism having a portion movably mounted in said receiver, a movable member forward of said receiver and adapted to bear against a portion of said breech mechanism to lock said breech mechanism in closed position and a port in said barrel to communicate the gas pressure within said barrel directly to said locking member, the locking action of said means being due solely to the gas pressure. 95
4. In an automatic firearm, a receiver, a barrel carried thereby, a breech mechanism having a portion movably mounted in said receiver, and means forward of said receiver operated by the gas pressure within the barrel for locking said breech mechanism in closed position until the gas pressure has decreased to the requisite power after the explosion of a cartridge, the locking action of said means being due solely to the gas pressure. 105
5. In an automatic firearm, a receiver, a barrel carried thereby, a breech bolt reciprocatively mounted in said receiver, an arm projecting forwardly from said bolt, a port in said barrel and a plunger in said port adapted to be forced against said arm by the initial high gas pressure within the barrel to lock said breech bolt in closed position until the gas pressure has decreased to the requisite extent, the locking action of said plunger being due solely to the gas pressure. 115
6. In an automatic firearm, a receiver, a barrel carried thereby, a breech bolt reciprocatively mounted in said receiver, an arm projecting forwardly from said bolt, a socket in said arm, a port in said barrel and a plunger in said port adapted to enter said 120
- 125
- 130

socket, the contacting surfaces of said plunger and socket being oblique to the axis of said plunger.

7. In an automatic firearm, a receiver, a barrel carried thereby, a breech bolt reciprocatively mounted in said receiver, an arm projecting forwardly from said bolt, a tongue and groove connection between said arm and barrel, a socket in said arm, a port in said barrel and a plunger in said port adapted to enter said socket, the contacting surfaces of said plunger and socket being oblique to the axis of said plunger.

8. In an automatic firearm, a receiver, a barrel carried thereby and having a port, a breech mechanism having a portion mounted in said receiver, and a movable member in said port adapted to be forced against a portion of said breech mechanism by gas pressure within the barrel to lock said mechanism in closed position, the locking action of said means being due solely to the gas pressure.

9. In an automatic firearm, a receiver, a barrel carried thereby and having a port, a breech mechanism having a portion mounted in said receiver, and means operated by the gas pressure within the barrel for locking said breech mechanism in closed position, said means comprising a plunger slidably mounted in said port, the locking action of said means being due solely to the gas pressure.

10. In an automatic firearm, a receiver, a barrel carried thereby, a breech mechanism having a portion mounted in said receiver, and means for locking said breech mechanism in desired position, said locking means comprising a movable member carried by the barrel and subject to the gas pressure within the barrel to force it into locking engagement with a portion of the breech mechanism, the locking action of said means being due solely to the gas pressure.

11. In an automatic firearm, a receiver, a barrel carried thereby, a breech mechanism having a portion mounted in said receiver, and means movable into engagement with a portion of said breech mechanism to lock it in closed position, said locking means being subjected directly to the pressure within the

barrel through the medium of a short column of gas immediately after firing, the locking action of said means being due solely to the gas pressure.

12. In an automatic firearm, a receiver, a barrel carried thereby, a breech mechanism having a portion mounted in said receiver, means movable by the gas pressure within the barrel for locking said breech mechanism in closed position, and a short passage for communicating the gas pressure to said locking means, the locking action of said means being due sole to the gas pressure.

13. In an automatic firearm, a receiver, a barrel carried thereby, a breech mechanism having a portion mounted in said receiver, and means movable by gas pressure within the barrel for locking said breech mechanism in closed position, said means comprising a plunger mounted in a port in said barrel, the locking action of said means being due solely to the gas pressure.

14. In an automatic firearm, a receiver, a barrel carried thereby, a breech mechanism having a portion mounted in said receiver, and means for locking said breech mechanism in closed position, said means comprising a movable member actuated through the medium of a short column of gas, the locking action of said means being due solely to the gas pressure.

15. In an automatic firearm, a receiver, a barrel carried thereby, a breech mechanism having a portion mounted in said receiver, and means directly subject to gas pressure within said barrel for locking said breech mechanism instantaneously after the firing of a cartridge, the locking action of said means being due solely to the gas pressure.

16. In an automatic firearm, a receiver, a barrel carried thereby, a breech mechanism having a portion mounted in said receiver, and means instantly operated by the gas pressure within the barrel after firing for locking said breech mechanism in closed position, the locking action of said means being due solely to the gas pressure.

In witness whereof, I hereunto affix my signature this 6th day of Jan., 1922.

CARL GUSTAF SWEBILIUS.
